UNITED STATES PATENT OFFICE.

ALVAN MARKLE, OF HAZLETON, PENNSYLVANIA.

CONTACT APPARATUS FOR ELECTRIC RAILWAYS.

SPECIFICATION forming part of Letters Patent No. 698,124, dated April 22, 1902.

Application filed January 19, 1901. Serial No. 43,834. (No model.)

To all whom it may concern:

Be it known that I, ALVAN MARKLE, a citizen of the United States, and a resident of Hazleton, in the county of Luzerne and State 5 of Pennsylvania, have invented certain new and useful Improvements in Contact Apparatus for Electric Railways, of which the following is a specification.

My invention relates to the construction of 10 contact devices for electric-railway circuits, particularly the so-called "third-rail-railway" systems, the object being to provide a reliable and effective means for securing a traveling connection between the supply-circuit and the moving vehicles.

In the accompanying drawings, illustrating 20 one application of the invention, Figure 1 is a cross-section of a portion of a railway-track and of such portion of the car-truck as is necessary for illustrating one application of the invention, and Fig. 2 is a plan thereof. Figs. 3, 4, and 5 illustrate modifications and details.

In Figs. 1, 2, and 3 I have shown a form of contact-shoe and support consisting of a plate 25 15, of iron or other suitable material, carried at its respective ends by links 16, which in turn are supported by a flexible spring 17, permitting the contact-shoe to yield more or less as it is pressed against the conductor.

30 The contact-shoe and spring are carried upon the arm 17^a, which is here shown as being pivoted in a bracket 18, the outer end being pressed upward by a counterweight 19. The pressure of the shoe against the conductor 35 may be assisted by a suitable tension-spring, if desired. The bracket 18 is carried upon any suitable portion 21 of the truck-frame. A chain or other convenient connection 22 leads from the contact-supporting arm 17^a to 40 a convenient place in the cab or car, so that the motorman or other attendant may at will drop the contact-shoe downward against the side of the truck and away from the main conductor. A flexible cable 23 may be employed for securing proper electrical connection 45 from the contact-shoe to the controllers and motors upon the car. This contact device may be employed in connection with various forms of supply-conductors.

50 In the drawings, 1 represents a track-rail supported upon ties in the usual manner, one of the ties being represented at 2. This tie

is shown as elongated sufficiently to support a post 3 at a convenient distance from the rail 1. The post is securely bolted to the tie 55 and may be strengthened by a brace 4. At its upper end there is secured the third rail or contact-conductor 5, shown in this instance as being in the form of an angle-iron, one side being securely bolted to the upper 60 end of the post, as shown. Above the angle-iron there may be placed a continuous covering-board 6, which is designed to protect the conductor from the weather and also to so guard it that accidental contact therewith 65 is prevented. The abutting ends of different sections of conductor may be united by splice-plates 7, fastened by bolts 8. A cap 9 is shown as being placed over the bolts. Any suitable form of electric bond—such, for instance, as a plastic bond 10—may be used for electrically connecting the successive sections 70 of the conductor. I have shown an inclined cover 11 extending along from post to post to more completely shield the vertical portion of 75 the rail 5 in cases where it is desired to more securely guard against accidental contact therewith. By mounting the posts 3 upon the projecting ends of the ties of the road the proper relative position of the conductor 5 80 from the track is insured, even though the latter may be thrown out of place by settling or by frost. Supply-conductors or feeders 12 12 may be carried by the posts 3, these conductors being insulated from the posts at the points 85 where they pass therethrough—as, for instance, by suitable thimbles of insulating material 12^a—and a face-plate or board 13 may cover these conductors. This face-plate may extend from post to post continuously, 90 if desired, thus fairly shielding the conductors. The contact-surface of the conductor 5 is the under side of the horizontal portion of the angle-iron and is therefore shielded from sleet and snow, and thus the chances of 95 interruptions of the electrical contact between the shoe and the conductor in snow and sleet storms are practically removed. If desired, a drip-plate or shield 14 may extend downward from the inner edge of the board 100 6 to more thoroughly protect the conductor 5.

Instead of mounting the conductor 5 upon posts of such height as represented in Figs. 1 and 2 they may be carried near the bed of

the road, as shown, for instance, in Figs. 3, 4, and 5, either between the track - rails or outside. In this instance a timber 24 is shown as being laid along the inner edge of one of the rails, and the conductor 5 is supported upon this timber. The contact-lever is carried by a support 18, fastened to a suitable portion of the truck—for instance, the bolster. The protecting-board 6 extends over the top of the angle-iron and leaves the under side of the latter free for contact, as before.

I claim as my invention—

1. In an electric-railway system, a contact device consisting of a contact-shoe, pivoted links at the respective ends of said shoe, and

a flexible spring to the respective ends of which said links are pivoted, substantially as described.

2. A contact-shoe for electric railways, consisting of a contact-plate, a yielding spring, and links connecting the ends of the spring with the contact-plate, substantially as described.

Signed at New York, in the county of New York and State of New York, this 18th day of January, A. D. 1901.

ALVAN MARKLE.
